UNITED STATES PATENT OFFICE.

JOSEPH H. GLAUBER, OF CLEVELAND, OHIO.

DESIGN FOR A LAVATORY-FITTING.

46,946.

Specification for Design.

Patented Feb. 16, 1915.

Application filed October 26, 1914. Serial No. 868,768. Term of patent 14 years.

To all whom it may concern:

Be it known that I, JOSEPH H. GLAUBER, a citizen of the United States, residing at Cleveland, county of Cuyahoga, and State of Ohio, have invented a new, original, and ornamental Design for a Lavatory-Fitting, of which the following is a specification, reference being had to the accompanying drawing, forming part thereof.

The single figure is a side view of a lavatory fitting showing my new design.

I claim:

The ornamental design for a lavatory fitting, as shown.

JOSEPH H. GLAUBER.

R. B. MOSER.

Copies of this patent may be obtained for five cents each, by addressing the "Commissioner of Patents, Washington, D. C."

Correction in Design Letters Patent No.
46,946.
40,946.

It is hereby certified that Design Letters Patent No. 46,946, granted February 16, 1915, for a design for a "Lavatory-Fitting," were erroneously issued to the inventor Joseph H. Glauber, of Cleveland, Ohio, whereas said Letters Patent should have been issued to The Citizens Saving & Trust Company, Executor of said Glauber, deceased, as shown by the records of assignments in this Office; and that the said Letters Patent should be read with this correction therein that the same may conform to the record of the case in the Patent Office.

Signed and sealed this 6th day of April, A. D., 1915.
